Des. 181,633
Patented Dec. 10, 1957

181,633

GOLF TEE

Duke M. de la Fariest, Ashland, Wis.
Application October 12, 1956, Serial No. 43,344

Term of patent 14 years

(Cl. D34—5)

Fig. 1 is a side elevational view of a golf tee showing my new design.

Fig. 2 is a top plan view of Fig. 1.

Fig. 3 is an enlarged transverse sectional view of the stem of the golf tee.

Fig. 4 is a bottom plan view of Fig. 1.

I claim:

The ornamental design for a golf tee, substantially as shown.
